ALFRED ANDREW GILMORE, OF PRESTON, ONTARIO, CANADA, ASSIGNOR TO THE METAL SHINGLE AND SIDING COMPANY, LIMITED, OF PRESTON, ONTARIO, CANADA.

TRUSS FOR BARNs.

1,369,421.

Specification of Letters Patent. Patented Feb. 22, 1921.

Application filed March 16, 1917. Serial No. 155,270.

To all whom it may concern:

Be it known that I, ALFRED ANDREW GILMORE, a subject of the King of Great Britain, residing at Preston, in the Province of Ontario and Dominion of Canada, have invented 5 a new and useful Truss for Barns, of which the following is a specification.

The present invention relates to an improved truss for use in barn construction, 10 and has particular reference to certain hereinafter pointed out improvements in the structure and mounting of the truss disclosed in the United States Patent, No. 1,079,040, granted Cyrus Dolph, November 18, 1913.

This Dolph patent discloses a truss for supporting and reinforcing the sides and roofs of barns. The Dolph truss is of such construction, and is so peculiarly mounted in 20 the barn, that it is necessary to provide a special truss for each different size of barn.

The object of this invention is to provide a truss possessing all of the advantages of this Dolph truss, and which in addition 25 thereto may be used as a standard truss for application to barns varying in size within a wide range.

Other objects and advantages of this invention will be brought out in the following 30 specific disclosure of the present preferred embodiment of the invention, the same being illustrated in the accompanying drawing, wherein—

Figure 1 is a vertical sectional view 35 through one side of the frame of a barn, showing a truss secured in position according to this invention, and showing a barn of relatively large size.

Fig. 2 is a fragmentary view of the upper 40 end of the roof of a barn of smaller dimensions than the structure of Fig. 1, showing the truss secured to the roof by the device of this invention, and showing the truss projecting above the lower edge of the upper rafter.

Fig. 3 is a similar view, showing another 45 adjustment of the truss upon a slightly larger barn than Fig. 2, and showing the upper end of the truss still projecting above the lower edge of the upper rafter.

Fig. 4 is a similar view, showing a further 50 adjustment of the truss upon a still larger barn than Fig. 2, and showing the upper end of the truss spaced below the upper rafters.

Fig. 5 is a detail perspective view, show-

ing the inner edge of a purlin secured across the upper inclined brace of the truss, the view disclosing the improved clasp and the means for adjusting the same longitudinally upon the brace to secure the truss in the various positions shown in Figs. 1, 2, 3 and 4.

Fig. 6 is a cross sectional view, enlarged, through the purlin of Fig. 5, and through one side of the upper inclined brace.

Referring to this drawing, wherein like 65 parts are designated by similar numerals of reference throughout the several views, and referring particularly to Fig. 1, 10 designates a cross sill supporting the flooring 11 in the usual manner. At one side of the 70 barn, a side post 12 is placed having on top thereof the usual wall cap 13, and from the wall cap rises the lower rafter 14, which supports at its upper end the upper rafter 15. These rafters, or rafter sections, form the 75 frame of the roof and carry the bars 16 upon which the roof 17 is directly secured.

For the purpose of reinforcing and supporting the post 12 and the rafters 14 and 15, a truss is provided. This truss comprises 80 a main truss member 18 made of angle iron, and of the cross section shown in Fig. 5, and extending from the lower end of the side post 12 upwardly to a position adjacent to the point of juncture of the lower and upper 85 rafters 14 and 15. The present invention provides a main truss member 18 of a uniform length for barns which differ in size, so that in applying the truss to a large barn, the member 18 terminates at a point below 90 the juncture of the rafters 14 and 15, while in small barn constructions the main truss member 18 extends above the juncture of the rafters 14 and 15, as clearly shown in Figs. 2, 3 and 4.

The lower end of the main truss member 18 is anchored to the post 12 and the sill 10 by means of a corner plate 19 preferably in the form of a vertical web having lateral flanges resting against the inner side of the post 12 and against the floor 11. These flanges are secured to the post and the sill by bolts, or the like, as indicated in Fig. 1. A brace 20 is secured to the sill 10 by an attaching plate 21, which latter is fastened 100 to the sill 10 at a point spaced inwardly from the post 12. The brace 20 extends upwardly and outwardly, and is secured to an intermediate attaching plate 22 which is 105 fixed upon the main truss member 18 at a 110

point intermediate the ends thereof, and preferably in a plane below the wall cap 13. This intermediate attaching plate 22 projects upwardly and outwardly from the 5 main truss member 18, and is secured to the inner end of a strut 23. The strut 23 extends upwardly and outwardly at a slight 10 inclination, and is secured to an outer attaching plate 24 secured to the upper end 15 of the post 12 and against the inner side of the wall cap 13. The back of the truss comprises an upper inclined brace 25 which has its lower end secured to the outer attaching plate 24, and which extends upwardly at the inner side of the roof and is 20 inclined toward the upper extremity of the main truss member 18. A connecting plate 26 joins the upper ends of the inclined brace 25 and the main truss member 18, so as to 25 rigidly hold the same together and transmit stress placed upon the upper brace member 15 to the main truss member.

According to this invention, the meeting 25 ends of the upper and lower rafters 15 and 14 are braced or secured together by a reinforcement, the same being disclosed in the present instance, as in the form of a substantially 30 triangularly shaped block 27 to take the place of the purlin usually employed at such juncture. This connection or reinforcement of the rafter sections forms the sections into practically a continuous rafter, and the engagement of the truss member at or near its upper end with the rafter, either 35 below or above the reinforcement 27, braces and supports the roof.

In Fig. 1, a relatively large barn construction is shown. In this instance, the upper end of the truss terminates below the reinforcement 27. To apply the truss to this 40 large barn, an adjustable purlin 29, disclosed in the present instance as composed of three strips or boards arranged in superposed relation, is secured across the lower 45 rafter 14 in spaced relation from the lower end of the reinforcing block 27, and in this instance, opposite to the upper extremity of the truss. The purlin is secured in such 50 position to the rafter 14 by any suitable means, such as the spikes shown. The lower 55 edge of the purlin bears flat against the outer webs or flanges of the upper inclined brace 25 which extends parallel to the adjacent rafter 14, and is secured to the brace 60 by means of a clasp 30. The clasp 30 in the present instance is shown in the form of a pair of substantially U-shaped laterally spaced apart clips having threaded extremities. These U-shaped clips are engaged over 65 the purlin 29, and the threaded ends of the clips are passed downwardly through the adjacent registering pairs of openings 70 formed through the outturned flanges or webs of the brace 25.

65 The clips are held in place by nuts 28,

or the like, threaded upon the ends of the clips 30, and binding against the lower or inner faces of the webs to draw the clips downwardly about the purlin 29. This clasp secures the upper end of the truss to 70 the purlin and thus supports and reinforces the roof.

If, as shown, in Fig. 2, the structure of the barn is such that the reinforcing block 27 is located below the upper end of the 75 truss, the purlin 29 is adjusted along the rafter 14 to a sufficient extent to engage the upper brace 25 of the truss, and at the same time space the upper extremity of the truss from the roof 17. A relatively small sized 80 roof construction is shown in Fig. 2, wherein the upper end of the truss extends between the rafter. The purlin 29 is so positioned that it transmits the pressure of the roof from the rafter to the back of the truss, and is 85 the only pressure transmitting connection between the truss and the roof. In this instance, the clasp 30 is adjusted longitudinally on the upper brace 25, to engage the purlin 29, and to secure the same to the 90 brace at its point of engagement thereagainst.

In Fig. 3, another adjustment is shown. The roof structure of this figure is larger than the roof structure shown in Fig. 2. 95 The purlin 29 is positioned at the lower end of the reinforcing block 27, and the brace 25 of the truss engages the purlin 29 at a point nearer the upper extremity of the brace than that shown in Fig. 2. The clasp 100 30 is accordingly adjusted longitudinally upon the brace 25 toward the upper end thereof and secured in such position. It will be noted that the upper end of the truss does not extend as far upwardly between 10 the rafters as in the smaller construction of Fig. 2. This apparently slight difference in adjustment accommodates the truss to barns varying several feet in width.

In Fig. 4, a still further enlarged roof 110 structure is shown. In this instance, the purlin 29 is located at the lower end of the reinforcing block 27. The upper inclined brace 25, however, engages the lower side or edge of the purlin 29 at a point still 115 nearer the upper end of the truss. The clasp 30 is adjusted along the brace 25 for engagement over the adjusted purlin.

It is thus seen that the truss may be made of one size or height, so as to provide a 120 standard truss, and that this truss, by the adjustment of the purlin 29, and the adjustment of the clasp 30, may be incorporated in barn structures which vary in size within a relatively wide range. It is readily seen 125 from Fig. 1 that as the reinforcing block 27 is used at the juncture of the lower and upper rafters 14 and 15, the purlin 29 may be adjusted downwardly on the lower rafter 14 to a considerable distance below the junc- 130

ture of the rafter sections, without weakening the roof structure. The upper inclined brace 25 has in the upwardly facing webs or flanges thereof, registering pairs of openings 31 arranged in sets spaced apart to correspond to different adjustments of the clasp 30 necessary to apply the truss to barn constructions of different sizes.

It is usual to build barns of from 30 to

10 50 feet wide. The truss may be constructed of a certain standard size corresponding to medium sized barns. By the adjustment of the clasp 30 and the adjustment of the purlin 29, this standard truss may be easily 15 adapted to barns of smaller size, or of larger size according to the requirements, and without the necessity of making a truss of special size for each size or width of barn.

What is claimed is:—

20 1. In barn construction employing lower and upper rafters, means for holding the same together, means running crosswise of the lower rafters and secured to each of said lower rafters, and a supporting structure 25 comprising a main truss and upper and lower braces, the second named means being securable at desired points along said upper braces.

2. In barn construction employing lower 30 and upper rafters, means secured to each pair of lower and upper rafters to unify said rafters, each of said means being independent of all the others, means running crosswise of the lower rafters and secured 35 to each of said lower rafters, and a supporting structure comprising a main truss and upper and lower braces, the second-named means being securable at desired points along said upper braces below the first- 40 named means.

3. In barn construction employing lower and upper rafters, means secured to each

pair of upper and lower rafters for holding the same together, purlins running crosswise of the lower rafters and secured to each 45 of said rafters below said means, and a supporting structure comprising a main truss and upper and lower braces, said purlins being adjustably secured at desired points along said upper braces and the lower 50 rafters.

4. In barn construction employing upper and lower rafters, means secured to each pair of upper and lower rafters to unify 55 said rafters, each of said means being independent of all the others, purlins running crosswise of the lower rafters and secured to each of said rafters below said means, and a supporting structure comprising a main truss and upper and lower braces, said pur- 60 lins being adjustably secured at desired points along said upper braces and lower rafters.

5. In barn construction employing upper and lower rafters, blocks secured to the ends 65 of each pair of lower and upper rafters to form substantially a continuous rafter, purlins running crosswise of the lower rafters and secured to each of said rafters below and close to said blocks, and a support- 70 ing structure comprising a main truss and upper and lower braces, said upper braces being provided with a series of spaced open- 75 ings, and clips engageable with said open- ings and with said purlins whereby the pur- lins are adjustably secured at desired points along said upper braces.

In testimony that I claim the foregoing as my own, I have hereto affixed my signature in the presence of two witnesses.

ALFRED ANDREW GILMORE.
